WINDOW

Filed July 6, 1926

Claude A. Lewis, INVENTOR.

BY

Jesse P. Stone

ATTORNEY.

UNITED STATES PATENT OFFICE.

CLAUDE A. LEWIS, OF HOUSTON, TEXAS, ASSIGNOR TO AMERICAN WINDOW COMPANY, A CORPORATION OF DELAWARE.

WINDOW.

Application filed July 6, 1926. Serial No. 120,599.

My invention relates to windows for use in building structures such as offices, factories and dwellings.

It is an object of the invention to provide a window, the sashes of which are reversible to expose the outer side inwardly for washing. It is also desired that the sash be quickly removable from the casing.

It is a further object to construct the sash and frame so that the windows are removable without danger of dropping or injury to the window or to the user.

It is also desired to form a window with a sash removable and so formed as to be weather tight to prevent entrance of wind or rain.

Referring to the drawings herewith, Fig. 1 shows a side view of a window, the frame being in vertical section, the sash being partly in elevation and partly in vertical section. Fig. 2 is a broken elevation of the joint of the upper sash. Fig. 3 is a side view of the upper end of the casing and the upper and lower sash. Fig. 4 is a transverse section on the line 4—4 of Fig. 1. Fig. 5 is a broken detail of one of the riders. Fig. 6 is a detail illustrating the attachment of the sash cord. Fig. 7 is a detail of the sash plate; and Fig. 8 is a broken detail in perspective of the window jamb between the two sashes. Like numerals of reference are applied to like parts in all the views.

The invention disclosed herein is an improvement upon the device set out in my prior application copending herewith, filed June 10th, 1926, as Serial No. 115,141. The lower sash 1 and upper sash 2 are mounted in the usual position within a window casing including a lower sill having a stool 3, an inclined ledge 4, jambs 5, and head plate 6. To the outer side of the casing is a head board 7, within which is a cross piece 8 grooved on its lower side to receive a stop plate 9 for the upper sash.

The lower sash 1 is provided at its sides with riders 10, which are detachably connected with said sash. Said riders comprise bars of the same length as the lower sash and having attached thereto at their upper ends a sash cord 11.

As shown in Fig. 6 the sash cord is fitted within a groove in the outer face of the rider, and the lower end of the cord is extended through an opening 12 in the rider. The

cord is further secured in position by transverse screws 13 extending through the rider into the cord. The sash cords extend over pulleys 14 in the side of the window jamb and are understood as having the usual sash weights thereon, not shown.

As shown in Fig. 5, the riders have therein lower grooves 15 having a bayonet form, the upper end of said slot opening forwardly at 16. The upper groove 17 is extended downwardly a short distance from the upper end of the rider and is open at its upper end. The forward side of the rider has a narrow flange 18 thereon which stops short of the upper end, in the manner shown in Fig. 5.

The lower sash is formed with upper and lower pins 19 and 20, respectively, said pins projecting beyond the sash and into the grooves 17 and 15, respectively, in the riders.

When the lower sash is to be raised, it is raised with the rider, each rider moving within a slideway 21 in the window jamb 5. Toward the upper end of said slideway is a stop member 22, the lower end of which acts to limit the upward movement of the rider. If it is desired to remove or reverse the lower sash, said sash is elevated slightly in the rider, as shown in dotted lines in Fig. 3. This brings the pin 19 out of the groove 17 of the rider and allows the upper end of the sash to be swung inwardly about the lower pin 20 as a pivot, and it is contemplated that the sash will be lowered to bring said pin to the lower end of the slot 15. The sash may be then swung downwardly until the upper end contacts with the window stool 3. This will make it possible to wash the outer side of the window pane.

If it is desired to remove the sash, the pin 20 will be moved upwardly in the slot 15 and out through the opening 16, thus releasing the window. It will be obvious that the sash may be again inserted in position by reversing the operation described.

The upper sash 2 is not adapted to slide in the casing. It has at its lower end a supporting plate 23 at each side. This plate is set into the side of the sash and screwed into position by wood screws 24. Said plate has a forwardly extending bracket 25, the forward end of which is rounded at 26 and a slot 27 is formed therein opening upwardly through the bracket and adapted to receive the pin 19 of the lower sash. On the lower

side of the bracket is formed a lateral arcuate flange 28. As shown in Fig. 8, the window jamb 5 is formed with a curved recess 29 therein to the rear of the slideway 21 of the 5 lower sash. The said recess is cut on the arc of a circle so as to allow the movement therein of the lower end of the upper sash and of the lateral flange 28 thereon.

When it is desired to move the upper sash, 10 the lower sash is left in position. The upper end of the sash 2 is then pulled inwardly, the sash swinging on the pivot formed by the pins 19. In so swinging it is to be noted that the flange 28 of the plate 23 will bear against 15 the surface 29 formed in the jamb. There will, therefore, be no lost motion at the joint when the sash is swung inwardly, as clearly noted from Fig. 2. When the sash has been moved inwardly until the sash has passed the 20 horizontal position, the flange 28 will move out of the recess 29, but when this occurs the weight of the window will be forwardly, tending to hold the plate in contact with the pin 19. If the sash is to be removed there- 25 after, this may be accomplished by lifting the sash to free it from the pins 19 in an obvi- ous manner. The sash may again be inserted in position by a reversal of this operation.

I contemplate making the window weather- 30 proof by placing upon the sides of the jamb adjacent the sash, strips 30 of metal, the inner edge of which is recurved and adapted to fit within a groove 31 in the upper sash when said sash is in closed position. A similar 35 strip 32 is adapted to fit within a similar groove, indicated at 33 in Fig. 4, in the lower sash.

It is also to be noted that the flange 18 upon the rider 10 closes the space between 40 the rider and the sash on its forward side so that no space is provided for the entrance of rain or wind.

The improvements made in the shape and the general construction of the rider makes 45 the lower sash easily operated and weather- proof. The mounting at the lower end of the upper sash prevents accidental release of falling of the sash while it is being opened.

It is believed that the advantages of the 50 construction will be apparent without further description.

What I claim as new and desire to protect by Letters Patent is:

1. A window including a casing, a lower 55 sash, laterally projecting pins thereon, an upper sash, plates at the lower end of said upper sash removably engaging said pins, said upper sash being adapted to swing on said pins, and means on said plates co-operating with said casing to hold said plates on said

pins, while said sash is swung to a horizontal position.

2. A window including a casing, a lower sash, laterally projecting pins thereon, an upper sash, plates at the lower end of said upper sash removably engaging said pins, said upper sash being adapted to swing on said pins, and means on said plates co-operating with said casing to hold said plates on said pins, while said sash is swung to a horizontal position, said means comprising an arcuate flange on each plate. 70

3. A window including a casing, a lower sash, laterally projecting pins thereon, an upper sash, plates at the lower end of said upper sash removably engaging said pins, said upper sash being adapted to swing on said pins, and means on said plates co-operating with said casing to hold said plates on said pins, while said sash is swung to a horizontal position, said means comprising an arcuate flange on each plate, said flange extending downwardly and laterally from the lower edge of said plate to fit within a recess 80 in said casing. 85

4. In a window, a casing, upper sash and lower sash therein, said lower sash having laterally extending pins at its upper and lower ends, riders for said lower sash having grooves at each end to receive said pins, plates at the lower end of said upper sash, brackets on said plates engaging the pins at the upper end of said lower sash and adapted to pivot thereon, there being a vertical recess between said lower sash and its said rider to receive said bracket, said recess being closed on the forward side, in the manner described, and means on said bracket co-acting with said casing to hold it in engagement with said pins when said sash is swung inwardly. 90

5. A window including a casing, a lower sash, an upper sash, plates at the lower end of said upper sash, and projecting forwardly therefrom, said plates having slots therein, pins adapted to be received in said slots and furnish pivots for said upper sash, and means on said plates engaging with said casing to hold said plates on said pins. 95

6. A window including a casing, a lower sash, an upper sash, plates at the lower end of said upper sash, and projecting forwardly therefrom, said plates having slots therein, pins adapted to be received in said slots and furnish pivots for said upper sash, and means on said plates extending laterally therefrom perpendicularly to the planes of said plates, to hold said plates on said pins. 110

In testimony whereof I hereunto affix my signature this 1 day of July, A. D. 1926.

CLAUDE A. LEWIS.
